UNITED STATES PATENT OFFICE.

EUGENE C. TALBOTT, OF SILOAM SPRINGS, ARKANSAS.

FOLDING STOOL FOR SEWING-MACHINES, PIANOS, OR ORGANS.

SPECIFICATION forming part of Letters Patent No. 672,110, dated April 16, 1901.

Application filed October 4, 1900. Serial No. 31,980. (No model.)

To all whom it may concern:

Be it known that I, EUGENE C. TALBOTT, a citizen of the United States, residing at Siloam Springs, in the county of Benton and State of Arkansas, have invented certain new and useful Improvements in Folding Stools for Sewing-Machines, Pianos, or Organs; and I do declare the following to be a full, clear, and exact description of the invention, such as will enable others skilled in the art to which it appertains to make and use the same.

The invention relates to folding stools for sewing-machines, pianos, and organs.

The object of the invention is to provide a stool which when not in use may be folded up under the table of a sewing-machine when used in connection with sewing-machines, or under the keyboard of a piano or organ when attached to either one of these instruments, and be entirely out of the way.

With this object in view the invention consists in certain features of construction and combination of parts, which will be hereinafter more fully set forth.

In the accompanying drawings, in which I have illustrated my invention applied to a sewing-machine, Figure 1 is a perspective view showing the stool in use, and Fig. 2 is a front view showing it folded up under the table of the sewing-machine.

Referring to the drawings, 1 denotes the frame of a sewing-machine, and 2 denotes a clamp, which consists of two bars 3 and 4, bolted to one of the side pieces of the sewing-machine frame, the inner bar having bolted thereto brackets 5.

6 and 7 denote, respectively, the inner and outer swinging arms, the former of which is hinged to the brackets 5 and to the arm 7 at the point 8, while the arm 7 is connected to a screw-threaded socket 9, which receives a screw-threaded stem 10 of the seat 11. The socket 9 is provided with a standard 12, the lower end of which is situated a few inches above the floor.

13 denotes legs, the upper ends of which are pivoted to a collar 14, held in vertical adjustment on the standard 12 by a set-screw 15.

Links 16 are pivoted to the legs intermediate their ends and to the lower end of the standard.

In Fig. 1 the device is shown in position for use, the hinged arm 6 extending parallel with

the side of one of the side pieces of the frame, and the hinged arm 7 arranged at right angles to the hinged arm 6, thus bringing the stool 55 out from under the sewing-machine table and in central location with respect to the same.

In Fig. 2 the stool is shown swung in under the table of the sewing-machine. Before swinging it in, the set-screw 15 is loosened, 60 thus permitting the collar 14 to be raised upward, which movement draws the legs together and raises their lower ends from engagement with the floor. In this position the set-screw is tightened against the standard 65 12 to hold the legs in their elevated position, thus permitting the stool to be swung in under the table without injury to the carpet.

From the foregoing description, taken in connection with the accompanying drawings, 70 the construction, operation, and advantages of my invention will be readily understood without requiring an extended explanation. The device is exceedingly useful for the purpose for which it is designed and may be 75 placed upon the market at a comparatively small cost.

Various changes in the form, proportion, and the minor details of construction may be resorted to without departing from the principle 80 or sacrificing any of the advantages of this invention.

Having thus fully described my invention, what I claim as new, and desire to secure by Letters Patent, is—

1. In a folding stool for sewing-machines, pianos and organs and the like, in which pedals or treadles are employed, the combination, with a bracket consisting of two parts hinged together, one part having a hinged connection 85 with the frame with which it is adapted to be used, and a seat connected to the other part and provided with vertically-adjustable legs, which, when the seat is moved to a position for use will support said seat and will remove 90 the strain from said bracket, and which may be adjusted vertically to elevate them to permit of the seat being swung under the frame and the legs occupy a position above the pedal or treadle thereof.

2. In a folding stool for sewing-machines, pianos and organs and the like, in which pedals or treadles are employed, the combination of a clamp formed of opposing bars adapted

to be applied to the side piece of the machine-frame, a bracket consisting of two parts hinged together, one part being hinged to the clamp, and a seat connected to the other part 5 and provided with vertically-adjustable legs, which, when the seat is moved to a position for use, will support said seat and remove the strain from said bracket, and which may be adjusted vertically to elevate them to permit 10 of the seat being swung under the frame and

the legs to occupy a position above the pedal or treadle thereof.

In testimony whereof I have hereunto set my hand in presence of two subscribing witnesses.

EUGENE C. TALBOTT.
